(57) **CLAIM**

The ornamental design for a USB PC cable, as shown and described.

DESCRIPTION

FIG. 1 is a front elevation view of a USB PC cable showing my new design;

FIG. 2 is a rear elevation view thereof;

FIG. 3 is a top plan view thereof;

FIG. 4 is a bottom plan view thereof;

FIG. 5 is a left side elevation view thereof;

FIG. 6 is a right side elevation view thereof; and,

FIG. 7 is a rear, bottom and left side perspective view thereof.

The broken line showing in FIG. 3 is for the purpose of illustrating environmental structure and forms no part of the claimed design.
